(57) **CLAIM**

I claim the ornamental design for adorned solar light stand, as shown and described.

DESCRIPTION

FIG. 1 is a perspective view of an adorned solar light stand showing my new design with a light feature shown in broken lines;

FIG. 2 is a front view thereof;

FIG. 3 is a back view of the design;

FIG. 4 is a right side view of the design;

FIG. 5 is a left side view of the design;

FIG. 6 is a top side view of the design; and,

FIG. 7 is a bottom view of the design.

The broken lines shown in the drawings represent portions of the adorned solar light stand that form no part of the claimed design.
